Primary Examiner—Paula A. Mortimer*Attorney, Agent, or Firm*—Wood, Herron & Evans, L.L.P.[57] CLAIM

The ornamental design for a throw for casket, as shown and described.

DESCRIPTION

FIG. 1 is a front elevational view of my new, original and ornamental design for a throw for casket;

FIG. 2 is a right side elevational view thereof, the left side being a mirror image;

FIG. 3 is a back elevational view thereof;

FIG. 4 is a top plan view thereof;

FIG. 5 is a bottom plan view thereof;

FIG. 6 is a front elevational view thereof with the upper portion folded rearward upon the lower portion;

FIG. 7 is a right side elevational view of FIG. 6, the left side being a mirror image;

FIG. 8 is a back elevational view of FIG. 6;

FIG. 9 is a top plan view of FIG. 6;

FIG. 10 is a bottom plan view of FIG. 6;

FIG. 11 is a front elevational view thereof with the upper portion folded forward upon the lower portion;

FIG. 12 is a right side elevational view of FIG. 11, the left side being a mirror image;

FIG. 13 is a back elevational view of FIG. 11;

FIG. 14 is a top plan view of FIG. 11; and,

FIG. 15 is a bottom plan view of FIG. 11.
